GEORGE S. MONSON, OF SAN FRANCISCO, CALIFORNIA.

RIVET-HOLDING TOOL.

1,267,573.

Specification of Letters Patent.

Patented May 28, 1918.

Application filed January 21, 1918. Serial No. 213,099.

To all whom it may concern:

Be it known that I, GEORGE S. MONSON, a citizen of the United States, residing at San Francisco, in the county of San Francisco and State of California, have invented new and useful Improvements in Rivet-Holding Tools, of which the following is a specification.

The present invention relates to an instrument for holding rivets when riveting.

Rivets are usually secured in structural metal by riveting machines, but when rivets are required to be affixed in plates, such as those of torpedo boat destroyers, which are very thin, then riveting by machinery tends to bend or distort the plates, and it is necessary to secure said rivets by hand.

The object of the present invention is to provide an instrument for holding the rivets in place in the holes of the plates to be riveted together so that they can be swaged or riveted by hand, which will be easily and rapidly adjusted to various locations of the rivets and to variations in the pressure which it is desired to apply to the rivet head.

In the accompanying drawing, Figure 1 is a top plan view of my improved rivet holder; Fig. 2 is a central longitudinal section thereof; Fig. 3 is a transverse section on the line 3—3 of Fig. 2.

Referring to the drawing, 1 indicates a tubular housing, threaded at its lower end, as shown at 2, and on said threaded end is screwed the wider end of a reducing union 3, into the narrower end of which is screwed one end of a tube 4 of any length which renders it suitable as an extension or support to rest against a plate or abutment. 6. Formed integrally with the tubular housing 1, and on one side thereof, is a longitudinally extending rack 7 having a slot 8 between it and the housing and having outwardly and forwardly extending teeth 10. Engaging in one of the notches 9 between said teeth is a pivot pin 11, which extends also through the rear terminal portions of flat bars 12, and through the terminal portions of said pin 11 and extending outside said bars 12 are passed upwardly the side members 13 of a yoke 14, the middle portion of which yoke carries a roller 16 which rolls in the slot 8. Springs 17 are coiled around the side members of the yoke and are compressed between the terminal portions of the pin 11 and nuts 18 screwed

on the side members 13 of the yoke. A retractor 19 is formed of a piece of wire, the terminal portions of which are formed into hooks 21 surrounding a cross-pin 22 connecting the two flat bars 12, while the middle portion of the wire is formed into a ring or loop to permit a finger to be applied thereto to pull the flat bars outward from the housing. Since the yoke cannot leave the housing while the pin 14 moves on the side members of the yoke with the flat bars, the coiled springs 17 are compressed by said movement, and, upon tension being removed from the flat bars said springs restore the pivot pin 11 into the nearest notch of the rack.

The forward ends of the flat bars are pivotally connected by a bolt 24 to a bar 26 having at the rear end a handle 27. Pivoted on said bar, as shown at 28, is the forked upper end of a hook 29 which can engage a cross pin 31 between the two flat bars. A rod 32 is pivotally attached, as shown at 33, to the other forked end of said hook, said rod passing through a guideway 34 supported by the bar 26, and pivoted at its inner end to a lever 36 pivoted, as shown at 37, to the bar 26 and having a handle 38 extending at an acute angle with the handle 27. A spring 39 is coiled around the rod 32 between the guideway 34 and the lever 36 and is compressed by said lever 36 when the handle 38 is moved toward the handle 27, as by grasping both handles in one hand. Thereby the rod 32 is moved longitudinally forward and the lower end of the hook 29 is moved rearward out of engagement with the cross pin 31. At the same time the spring 39 is compressed. The forward end of said bar 26 is rigidly secured or formed in one piece with the middle portion of a yoke 41, of which the terminal portions are pivoted on trunnions 42 extending from opposite sides of a collar 43, slideable upon a cylindrical body 44, the rear portion of which is received within the housing 1. The front end of the body has a socket 46 in which is received the contracted cylindrical rear end 47 of a rivet holder 48, the main portion of which is frusto-conical in form, its forward narrow end having a frusto-conical socket 49, to receive a correspondingly shaped head of a rivet 51. A spring 52 is coiled around the body and is compressed between the slideable collar 43 and a flange 53 formed on the front end of the body. A collar 54 is secured by

a set screw 56 around the body to retain the collar 43 in its position upon the body. In the rear end of the body is screwed the front end of a rod 57, upon the rear end of which a collar 58 is retained by a nut 59 screwed upon said rear end. Around said rod is a cylindrical block 61 and between said block and collar 58 is a compressed coiled spring 62.

10 The following is the mode of use of my improved rivet holding instrument. The operator of the instrument adjusts the instrument in place so that the tube 4 rests against a bulkhead 6 or other abutment, 15 while the front end of the rivet holder 48 is adjacent to the hole through which the rivet is to be driven, but spaced therefrom a sufficient distance to allow the rivet to be placed in said hole. When the red hot rivet has 20 been placed by an attendant in said hole, the operator, having first grasped both handles 27 and 38 with the same hand so as to withdraw the hook 29 from the pin 31, presses the handle 27 toward the housing 1 and 25 thereby moves the rivet holder to a position such that its socketed front end abuts against the head of the rivet, at the same time compressing the spring 52. He then releases his grasp upon the handle 38 so that the 30 hook 29 is caused by the spring 39 to engage the cross pin 31, thereby preventing the bar 26 from moving away from the housing 1 and holding the collar 43 in the proper position to compress the spring 52 so that the 35 rivet head is now held in its position against a plate 63 containing the rivet hole by the pressure of said spring. The attendant now 40 swages the end of the rivet projecting through said hole securing the rivet in position. The operator then again grasps both 45 handles 27 and 38, withdrawing the hook from the cross pin and allowing the bar 26 and the flat bars 12 to move outwardly from the housing, thereby withdrawing the rivet holder from its position around the rivet head.

With each blow of the hammer upon the rivet there is also imparted to the rivet holder and body a momentum which is also 50 imparted to the cylindrical block 61. This block, being loose, and its rearward movement being only opposed by the pressure of the coiled spring 62, moves slightly rearward, momentarily compressing said spring 55 62, and returning again under the increased pressure of said spring and imparting its forward momentum to the body 44 and rivet holder 48, thereby imparting a forward blow to the rivet head, tending to press said 60 rivet head against the plate 63.

The pressure of the spring 52 may be 55 varied by varying the notch 9 in the rack 7 which is engaged by the pivot pin 11. To adjust the pivot pin 11 in the rack to vary 65 said pressure, if it is required to increase

the pressure, all that is necessary is to move the flat bars 12 forwardly, for by such movement the cross pin is drawn forwardly against the pressure of the springs 19 over the rear surface of the tooth in front of the notch in which it is engaged and then drops under such pressure into the next notch in advance, and so on, until the desired notch is reached. But if it be desired to reduce the pressure, then the pivot pin 11 must be 75 withdrawn from the notch by pulling out the rear ends of the flat bars 12 by means of the retractor 19 whereupon the cross pin can be moved rearwardly and dropped into any notch that may be desired. 80

I claim:

1. In a rivet holding instrument, the combination of a housing, a body slidable therein, means carried by the front end of said body for holding a rivet, a collar slidable upon the body, a bar the front end of which is pivotally connected to said collar, a second bar pivotally connected at its front end to said first-named bar; the rear end of said bar being supported by the housing, a spring 90 coiled around said body and compressed between the collar and a portion of the body, and detachable means for securing together the two bars at an acute angle with each other. 95

2. In a rivet holding instrument, the combination of a housing, a body slidable therein, means carried by the front end of said body for holding a rivet, a collar slidable upon the body, a bar the front end of which is pivotally connected to said collar, a second bar pivotally connected at its front end to said first-named bar, the rear end of said bar being supported by the housing, a spring 100 coiled around said body and compressed between the collar and a portion of the body, detachable means for securing together the two bars at an acute angle with each other, a hammer block movably attached to said body and a spring for holding said hammer block to said body. 105

3. In a rivet holding instrument, the combination of a housing, a body slidable therein, a rivet holder carried by the front end of said body, a collar slidable upon the 115 body and having trunnions, a bar the front end of which is yoke-shaped and pivotally engages said trunnions, a second bar pivotally connected at its front end to said first-named bar, the rear end of said bar being 120 adjustably supported by the housing, a spring coiled around said body and compressed between the collar and a portion of the body, and detachable means for securing together the two bars at an acute angle with 125 each other.

4. In a rivet holding instrument, the combination of a housing, a body slidable therein, means carried by the front end of said body for holding a rivet, a collar slidable 130

upon the body, a bar the front end of which is pivotally connected to said collar, a second bar pivotally connected at its front end to said first-named bar, the rear end of said 5 bar being supported by the housing, a spring coiled around said body and compressed between the collar and a portion of the body, a rack carried by the housing, a bar pivotally connected at its front end to the afore- 10 said bar, a pivot pin carried by the rear end of said last-recited bar and adapted to engage any one of the notches in the rack, a

pin extending from said last-recited bar, a hook pivoted to the first-named bar and adapted to engage said pin, a rod pivotally 15 connected to said hook to vibrate the same on its pivot, a spring for moving the rod in the direction in which said hook engages said pin, a handle for moving said hook in the opposite direction, and means for yieldingly pressing said pin into engagement with a notch of said rack. 20
